UNITED STATES PATENT OFFICE.

CLARKSON W. MACY, OF CONVERSE, INDIANA.

CLOSET ATTACHMENT.

1,241,232.

Specification of Letters Patent. Patented Sept. 25, 1917.

Application filed May 10, 1917. Serial No. 167,762.

To all whom it may concern:

Be it known that I, CLARKSON W. MACY, a citizen of the United States, residing at Converse, in the county of Miami and State 5 of Indiana, have invented a new and useful Closet Attachment, of which the following is a specification.

The device forming the subject matter of this application is adapted to be employed 10 for supplying a disinfectant to a bowl by way of an atomizer, and the present invention aims to provide novel means for supplying air to the atomizer, and to provide novel means, under the control of an operator, for 15 regulating the air supply.

With the foregoing and other objects in view which will appear as the description proceeds, the invention resides in the combination and arrangement of parts and in 20 the details of construction hereinafter described and claimed, it being understood that changes in the precise embodiment of the invention herein disclosed, can be made within the scope of what is claimed, without 25 departing from the spirit of the invention.

In the drawings:—

Figure 1 shows in front elevation a structure embodying the present invention;

30 Fig. 2 is a fragmental vertical section taken through the adjacent portions of the water and air tanks;

Fig. 3 is a side elevation of the device shown in Fig. 1;

35 Fig. 4 is a section taken through the air valve; and

Fig. 5 is a section taken through the valve which controls the water supply and drainage.

40 The numeral 1 denotes a container comprising a water tank 2 supported on a pedestal 3, and an air tank 4, the tanks 2 and 4 being connected by a short pipe 5 within which is located a seat 6. At its lower end, 45 the pipe 5 is supplied with a spider 7. A float valve 8 is upwardly movable to coöperate with the seat 6 and includes a stem 9 slidable in the spider 7. Disposed above the seat 6 and downwardly movable to coöperate 50 with the seat is a valve 10 held in an open position by and supported from a retractile spring 11 connected with a hanger 12 carried by the pipe 5.

An air pipe 14 communicates at its upper 55 end with the air tank 4 and communicates at its lower end with a valve casing 15 in

which a valve 16 is journaled. An air pipe 17 communicates with the casing 15 and with an atomizer 18 including a nozzle 19 extended across the upper end of a nozzle dis- 60 charging into the bowl.

The numeral 22 denotes a water supply pipe opening into the tank 2 and connecting with a casing 23 in which a valve 24 is journaled. A water supply pipe 25 com- 65 municates with the casing 23 and a drain pipe 26 communicates also with the casing, the pipes 26 and 25 being oppositely disposed.

Mounted on the bowl 21 are bearings 27 70 in which a shaft 28 is journaled, the shaft being connected by means of hangers 29 with a movable member, such as a seat 30. The shaft 28 is journaled terminally in a bearing 31 carried by the pedestal 3. The 75 shaft 28 has a crank arm 32. A crank arm 33 is connected with the valve 24, and a crank arm 34 is connected with the valve 16. A link 35 is pivotally united with the crank arms 32, 33 and 34. 80

When the movable member 30 is in the elevated position shown in Figs. 1 and 3, the valve 24 is so disposed that a communication is established between the water supply pipes 22 and 25, the drain pipe 26 be- 85 ing closed by the valve 24. The valve 16 is so disposed with respect to the air pipes 14 and 17 that air cannot flow from the tank 4 to the atomizer 18. Under the circumstances above described, water flows 90 into the tank 2 and the air in the tank 2 is forced into the tank 4 through the pipe 5, pressure being created in the tank 4. This operation continues until the pressure in the tank 4 offsets the water pressure created 95 in the tank 2.

When the movable member 30 is swung to a closed position, the shaft 28 is rotated, and motion is imparted to the crank arms 33 and 34, from the crank arm 32, by way 100 of the link 35. By this operation, the valve 24 is made to close off the water supply pipe 25, and is made to open the drain pipe 26. At the same time, the valve 16 is so disposed that air can flow to the atomizer 18 by way 105 of the pipes 14 and 17, the contents of the atomizer 18 being discharged into the bowl 21 through the nozzle 19. Since the pressure in the tank 2 is relieved when the water starts to flow through the pipe 22 and 110 through the drain pipe 26, the valve 10 responds to the pressure in the air tank 4 and

moves to a closed position on the seat 6. This prevents the pressure in the tank 4 from being diminished through the pipe 22 and drain pipe 26. As soon as the pressure in the tank 4 has been diminished to a sufficient extent, by the flow of air through the pipes 14 and 17 to the atomizer 18, the valve 10, responding to the spring 11, moves into the open position shown in Fig. 2. An air vent is now established through the nozzle 19, the pipe 17, the valve 16, the pipe 14, the tank 4 and the pipe 5, which permits the water to drain out of the tank 2 through the pipe 22 and the pipe 26.

15 When the movable member 30 is disposed in the elevated position shown in Figs. 1 and 2, the water supply conduit 22—25 is open, the air outlet 14—17 is closed, and the drain pipe 26 is closed, whereupon the tank 2 fills, 20 and air pressure is stored in the tank 4 in the manner hereinbefore set forth.

The valve 8 is a float valve and moves to a closed position as the water rises in the tank 2, the function of the valve 8 being to 25 prevent water from rising in the tank 4.

Having thus described the invention, what is claimed is:—

1. In a device of the class described, a container including a water space and an

air space; means for supplying water to the 30 water space; means for draining the water space; a first valve coöperating with each of said means to dispose the same one at a time in communication with the water space; a bowl; an atomizer discharging into the 35 bowl; an air conduit leading from the air space to the atomizer; a second valve in the air conduit; a member movable with respect to the bowl and under the control of an operator; and an operative communication 40 between said member and both valves whereby the valves will be actuated when the movable member is actuated.

2. A device constructed as described in claim 1, in combination with a normally 45 open valve controlling the passage of air from the air space to the water space and movable to a closed position, responsive to pressure in the air space, when pressure in the water space is reduced.

In testimony that I claim the foregoing as my own, I have hereto affixed my signature in the presence of two witnesses.

CLARKSON W. MACY.
